(57) **CLAIM**

The ornamental design for a folding motorcycle mirror, as shown and described.

DESCRIPTION

FIG. 1 is a front view of a folding motorcycle mirror, showing my new design;

FIG. 2 is a back view thereof;

FIG. 3 is a top view thereof, shown enlarged for ease of illustration;

FIG. 4 is a bottom view thereof, shown enlarged for ease of illustration;

FIG. 5 is a right side view thereof, shown enlarged for ease of illustration;

FIG. 6 is a front and top perspective view thereof; and,

FIG. 7 is a back and bottom perspective view thereof.

The broken lines illustrate portions of the folding motorcycle mirror which form no part of the claimed design.
